MACHINE FOR WINDING FIN STOCKS

Joseph D. Lear, Buffalo, N. Y., assignor, by mesne assignments, to Fedders-Quigan Corporation, Buffalo, N. Y., a corporation of New York

Application August 16, 1943, Serial No. 498,845

13 Claims. (Cl. 153—64.5)

1

This invention relates to the manufacture of spiral or helical finned tubing and more particularly to the winding of the fin stock in ribbon form spirally on the periphery of a tube. In my prior Patent No. 2,152,437, I have disclosed and claimed apparatus for winding fin stock upon the periphery of a tube by mounting the tube for rotation and moving the fin applying mechanism along the rotating tube to wind the fin stock thereon. The present invention is in the nature of an improvement upon the subject matter of said prior patent.

An object of this invention is to provide an improved mechanism for winding the fin stock spirally and progressively on the periphery of a tube; with which the mechanism remains relatively stationary and the tube is moved progressively through the mechanism; which will wind the ribbon stock snugly and uniformly on the rotating and endwise moving tube; and which will be relatively simple, compact, light in weight, rapid in action and inexpensive.

Another object of this invention is to provide an improved machine for applying fin stock progressively and spirally to the periphery of a tube, which will require a minimum of power to operate, and which will produce a product of high quality, with the fin properly positioned and spaced thereon.

Another object of the invention is to provide an improved method of winding fin stock spirally on a tube, which will be relatively simple, efficient, practical, rapid and inexpensive.

Other objects and advantages will be apparent from the following description of one embodiment of the invention, and the novel features will be particularly pointed out hereinafter in connection with the appended claims.

In the accompanying drawings:

Fig. 1 is a plan of a mechanism for applying fin stock spirally and progressively to the periphery of a tube in accordance with this invention;

Fig. 2 is a side elevation of the same;

Fig. 3 is a sectional elevation through the fin stock applying mechanism, the section being taken approximately along the line 3—3 of Fig. 1;

Fig. 4 is a longitudinal sectional elevation through a portion of the mechanism of Fig. 3;

Fig. 5 is a transverse sectional elevation through a portion of the mechanism of Fig. 3, the section being taken approximately along the line 5—5 of Fig. 3;

Fig. 6 is a sectional plan of a portion of the mechanism of Fig. 3, the section being taken approximately along the line 6—6 of Fig. 3;

2

Fig. 7 is a sectional elevation of a portion of the mechanism of Fig. 6, the section being taken approximately along the line 7—7 of Fig. 6;

Fig. 8 is a perspective illustrating the manner in which the fin stock is wound on the tube; and

Fig. 9 is a transverse, sectional elevation of the mechanism shown in Fig. 3, with the section taken approximately along the line 9—9 of Fig. 3.

Referring first to Figs. 1 and 2, which illustrate a general diagrammatic layout of an improved winding machine constructed in accordance with this invention, associated with desirable auxiliary mechanism, the improved winding mechanism W is mounted upon a base 1. At one side of the base 1 is a suitable trough-like guide 2 supported by pillars 3. A tube 4 to which a spiral fin is to be applied is placed in the trough 2 and moved endwise to the mechanism W, and after passing through that mechanism where the fin stock in ribbon form is wound spirally on the tube, the tube 4 passes through a fluxing device 5 also mounted on the base 1, and then through a soldering device 6 mounted on a base 7. From the soldering device 6, the tube with the fin soldered thereon passes to, and is supported by another trough or upwardly opening channel guide 8 supported on pedestals 9.

Referring now to Figs. 3 to 9 particularly, the mechanism W for applying the fin stock spirally to the tube 4 includes a tubular sleeve or bushing 10, Fig. 3, having a bore of a size to receive and slidably and rotatably mount a stretch of tube 4 which is fed endwise therethrough. The bore of the bushing 10 is disposed in endwise alignment

35 with the trough 2 so that tubes pushed endwise along the trough 2 will enter the bore of the bushing 10. This bushing 10 is disposed within a housing or casing 11, which is supported on the base 1 and has an opening 12 through which the end

40 of the bushing 10 is exposed to receive the tube 4. The housing 11 has an upright supporting flange 13 which divides the housing into compartments 14 and 15. This flange 13 is provided concentrically of the bushing 10 with a laterally elongated bearing hub 16, which mounts a rolling bearing 17. Rotatably supported by the rolling bearing 17 is a bushing 18 which is approximately coextensive in length with the sleeve 10.

The outer end of the sleeve 10 is provided with a laterally turned peripheral flange 19, which abuts against the end of the bushing 18 and a cup-shaped shell 20 telescopes over the flange 19 and the adjacent end of the bushing 18 and is threaded up on the bushing 18 so as to clamp the flange

45 19 against the end of bushing 18. This shell 20

50 55 laterally turned peripheral flange 19, which abuts against the end of the bushing 18 and a cup-shaped shell 20 telescopes over the flange 19 and the adjacent end of the bushing 18 and is threaded up on the bushing 18 so as to clamp the flange

55 59 against the end of bushing 18. This shell 20

has an opening in its end wall of approximately the same size as the bore of the sleeve 10, which opening is larger at its outer end than at its inner end and tapered between them so as to receive the end of a tube 4 and guide it into the bore of the sleeve 10. A gear 21 is clamped against a shoulder on the periphery of the bushing 18 by the shell 20, the gear 21 being disposed in the chamber 14. Another gear 22 is rotatably mounted upon the periphery of the bushing 18 at the opposite side of the bearing 17 from the gear 21 and within the chamber 15 of this housing.

A pinion 23 is threaded upon a laterally extending hub on the gear 22, which pinion 23 is disposed or spaced in a direction lengthwise of the tube 4 from the gear 22 and within a chamber 24 of a rotatable housing 25. This housing 25 is formed of a laterally extending flange 26 on the inner end of the bushing 18, which flange has, at its outer periphery, a laterally turned rim or flange 27 which is concentric with the axis of the tube 4. A plate 28 secured to the end of this laterally extending flange 27 extends radially toward the tube 4 in a position between the pinion 23 and gear 22 and a suitable seal 29 is provided between it and housing 11. The chamber 24 is thus in communication with the chamber 15 in the space surrounding the pinion 23 and gear 22. Also forming a part of the housing 25 is a somewhat cup-shaped shell 30 which telescopes over the flange 27. The bottom of this shell extends toward the tube 4 and carries at its center, and concentric with the tube 4, a removable bushing 31, which at its right-hand end in Fig. 3 has a converging, tapered entrance to a bore of a size which receives and slidably and rotatably supports the tube 4, so that as the tube is inserted in the sleeve 10, it will be guided into the bore of the bushing 31 and thus farther through the machine.

The shell 30 has a laterally extending hub 32, which is rotatably mounted by a rolling bearing 33 in a bearing standard or upright 34. The free end of the hub 32 is threaded, and upon this threaded end is a tubular member 35. Threaded into the free end of this tubular member 35 is a short bushing 36 which has a bore that is the same size as, and aligned with, the most restricted part of the remainder of the bore of this tubular member 35, so that the bore of the bushing forms a continuation of the smallest bore portion of the member 35. This bushing 36 has a laterally and outwardly turned flange which serves as an abutment against which the fin stock is guided as it is wound upon the periphery of the tube 4. The tubular member 35 has a portion 37 extending in opposite directions from the central portion, see Fig. 5, and rotatably mounted on this portion 37, but on diametrically opposite sides of the tube 4, are bell crank levers 38.

The pivot pins 39 of these bell crank levers are carried by the portion 37, and the axes of the pins 39 are crosswise of but offset from the axis of the tube 4. One arm of each bell crank lever extends toward the tube 4 and at its free end rotatably supports a roller 40 by a pin 41. The tubular member 35, immediately adjacent the inner end of the bushing 36 is provided with recesses or cross passages 42, see Fig. 5, so that the rollers 40 can pass through these recesses and engage the periphery of the tube 4 passing through the tubular member 35. The periphery of each of these rollers 40 is concave in transverse cross section, with a curvature such as to approximately fit the convex periphery of the tube 4, and the

periphery of each roller 40 is also fluted or ribbed in a peripheral direction so as to provide small peripherally extending ribs which, if the rollers are pressed against the tube periphery, will grip or bite into the tube sufficiently to rotate the tube about its longitudinal axis when the rollers are bodily rotated with the tubular member about the longitudinal axis of the tube 4.

The other arm of each bell crank lever 38 extends generally parallel to the tube 4 and at its end is sufficiently heavy or weighted, so as to overbalance to a substantial extent the end carrying the roller 40. Thus when the tubular member 35 is rotated with the shell 30 of housing 25 about the axis of the tube 4, the bell crank levers will be rocked by centrifugal forces in directions to press the rollers 40 tightly against the periphery of the tube 4 which is between them in the tubular member 35. The faster the rotation, the greater will be the gripping force of the rollers 40 against the tube by reason of the increasing centrifugal forces. Hence the tube 4 will be rotated positively with the tubular member 35 about the axis of the tube, notwithstanding that the rollers 40 are free to rotate about their own axes or pivot pins 41, and thus pass the tube 4 endwise while rotating it.

In order to provide for an initial grip between the rollers 40 and the tube 4 when the machine is idle or rotating at a very low rate, each weighted end of each bell crank lever may be provided on its side towards tube 4, with a recess containing a spring 42 which is under compression between an adjustable plug at the bottom of the recess and the hub of member 35. Each spring 42 urges its related bell crank lever in a direction to press the roller 40 on that lever against the tube 4. The rollers 40 are disposed as closely as possible adjacent the end of the tubular member 35 from which the tube 4 leaves or the exit end of the bore of bushing 36, so that the turning torque on the tube will be effective as closely as possible to the portion of the tube leaving the end of the bushing 36 where the fin is wound thereon. By arranging the rollers as closely as possible to the point where the turning torque is applied through the pull of the fin stock as it is wound on the tube, there will not be an opportunity for large torsional movements of the tube 4 with resulting inaccuracies or variations in the rotation of the tube 4 or in the winding of the fin ribbon on the tube. By mounting the levers 38 with the rollers close to the bushing 36, and the levers extending therefrom along the tube in a direction opposite to the direction of endwise travel of the tube, the pivots 39 can be intermediate the ends of the levers, and the rollers can be carried by the member 35 for bodily rotation therewith, yet close to the exit end of that member 35.

It will be observed from the foregoing that the gear 21 in the chamber 14 is fixed upon the bushing 18 which is rotatably mounted in the rolling bearing 17, and this bushing through the flange 26 and shell 30 of the housing 25, rotates the hub 32 which is also rotatably supported by the bearing 33 and mounts the tubular member 35.

Referring now particularly to Figs. 6 and 7, the pinion 23 meshes with and drives an idler gear 43 pivoted on a stud 44 carried by a bearing portion formed on the flange 26 of the housing 25, and this gear 43 in turn meshes with a gear 45 fixed on a shaft 46 rotatably carried by the bearing portion formed on the flange 26. This shaft 46 extends through the flange 26 into the chamber 75 formed by the shell 30 as it telescopes over the

flange 26, and in the portion within the shell 30, this shaft 46 carries, fixed thereon, a worm screw 47, see Figs. 6 and 9.

Referring now particularly to Fig. 9, this worm screw 47 meshes with and drives a small worm wheel 48 which is secured fixedly upon a shaft 49. This shaft 49 has at one end a head 50 which abuts against an end face of the gear 48.

Adjoining the head 50, the shaft 49 is threaded as at 51, and is then provided with a reduced threaded portion 52 with a shoulder 53 between these two threaded portions. Beyond the threaded portion 52, the shaft is provided with a smooth periphery where it passes through spaced bearing bushings 54 provided in an internal flange 55 on the inside face of housing 25. This smooth shaft portion, adjacent its free end, is provided with a still further reduced portion 56 on which a bevel gear 57 is secured and the extreme end of this shaft 49 is threaded and mounts a nut 58. Threaded upon the larger threaded portion 51 of shaft 49 is a bushing 59 which abuts at one end against the gear 48 and clamps it against the head 50 of the shaft. The gear 48 has a threaded bore so that it is threaded upon the threaded portion 51 against the head 50 of the shaft 49 and locked in that position by the engagement therewith of an end of the bushing 59. The bushing 59 which thus functions as a lock nut may be held against turning by a transverse pin 60 which passes through the bushing and the shaft.

The lock nut bushing 59 is rotatably received in a bearing lining or bushing 61, carried by a bearing boss 62 provided on the inner face of housing 25. Threaded upon the reduced threaded portion 52 of the shaft and against the shoulder 53 is a bevel gear 63, and a shim or thrust washer 64 is disposed between one end face of the bevel gear 63 and the end of the adjacent bearing bushing 54. By tightening the nut 58 on the smallest end of the shaft 49, the shaft will be pulled endwise so as to bring the shoulder 53 against the bevel gear 63 and clamp the bevel gear between it and the thrust washer 64, and at the same time press the bevel gear 57 against the end of the bushing 59. A pin 65 may be passed through the bevel gear 57 and the shaft 49 to definitely secure the bevel gear 57 to the shaft in addition to the clamping of that gear against the shoulder between the two reduced smooth sections under the pressure of the nut 58. Keyed upon the smooth part of the shaft 49 between the bearings 54 by a key 49a is a roller 66 with a periphery that is arcuately concave in transverse section. The center of curvature of this concave curvature is approximately that of the tube 4 where it contacts the tube so that it will fit the tube as shown clearly in Fig. 9.

Mounted on an inner wall face of the housing 25 by pivot screws or studs 67 (Fig. 9) are two bell crank levers 68 and 69. These bell crank levers 68 and 69 have arms normally extending approximately parallel to one another at opposite side faces of the roller 66 and at the free ends of these arms have weights 70 which are urged apart by a compression spring 71 that at its ends is received in recesses in the weights 70. The other arm of the bell crank 69 is provided with a bearing 72 which rotatably supports a shaft 73 that has fixed on one end thereof a bevel gear 74. Gear 74 meshes with and is driven by the bevel gear or pinion 63 on the shaft 49. The bevel gear 74 is at one end of the bearing 72 and mounted upon the shaft 73 at the other end of the bearing is a

roller 75 that is similar in diameter and periphery to roller 66. The shaft 73 at one end has a reduced, threaded portion upon which the roller 75 is threaded against a shoulder between the reduced threaded portion and the bearing part of the shaft to key this roller to its shaft. A nut 76 is threaded upon the threaded end of the shaft 73 and acts as a lock nut to prevent unthreading of the roller 75. This roller 75 also bears against the periphery of the tube 4.

Similarly, the other arm of the bell crank 68 is also provided with a bearing 77 similar to bearing 72 which rotatably supports a shaft 78. This shaft at one end carries a bevel gear 79 fixed thereon and which meshes with the bevel gear 57. At the other end of the bearing 77, the shaft 78 mounts a roller 80 which is threaded on the reduced end portion of the shaft 78 in the same manner that was explained for the mounting of the roller 75 of the shaft 73. The roller 80 is secured against unscrewing by a lock nut 81 threaded upon the shaft 78. The rollers 75 and 80 have peripheries which are concave in cross section, so as to fit the periphery of the tube 4, and of the same diameter as roller 66. It will be noted from Fig. 9, that these rollers 66, 75 and 80 are disposed 120 degrees apart around the periphery of the tube 4 and bear radially against the tube 4. The periphery of each of these rollers 66, 75 and 80 is preferably provided with crosswise ribs which grip or bite into the periphery of the tube 4 sufficiently to feed the tube 4 endwise when all of the rollers 66, 75 and 80 are rotated.

It will be noted that the worm screw 47 drives the worm gear 48, and the latter through its mounting on the shaft 49 drives the bevel gears 63 and 57. The bevel gear 57 drives the bevel gear 79 and through it and the shaft 78 drives the roller 80. The bevel gear 63 drives the bevel gear 74 and through it drives the roller 75. The roller 66 is keyed on the shaft 49, and thus all of the rollers when rotated in this manner will feed the tube 4 in the same direction, which will be to the left in Fig. 3. The spring 71 normally rocks the bell crank levers 68 and 69 in directions to press the rollers 66 and 75 radially against the periphery of the tube 4 and thereby to press the tube 4 against the periphery of the roller 66. When the housing 25 is rotated, the bell cranks 68 and 69 will be bodily rotated about the axis of the tube 4, and this rotation will create centrifugal forces on the weights 70 tending to separate them and move them towards positions in which the weights 70 would be actually aligned with the pivots 67 and the axis of the tube 4. This movement will tend to force the rollers 75 and 80 against the periphery of the tube 4 with a greater force than that created by the spring 71.

There is sufficient play between the bevel gears 57 and 79 and between the bevel gears 63 and 74 to allow of a limited rocking movement of the bell crank levers without causing disengagement of the meshing bevel gears. Thus the tube 4 will be gripped tightly by the rollers, and since the rollers are transversely ribbed, the positive rotation of all of these rollers will feed the tube endwise at a rate determined by the rotation of the worm screw 47. Since this worm screw 47 receives its motion from the pinion 23 and the gear 22, this rotation will depend upon the rate at which the gear 22 rotates.

Referring now to Fig. 6, the gear 22 meshes with an idler gear 82 which is fixed upon a shaft

83 that passes through and is rotatably supported by a bearing 84 carried by the flange 13. The other end of the shaft 83 has fixed thereon a gear 85, which meshes with and drives the gear 21 that is fixed upon the bushing 18. The idler gear 82 meshes with and is driven by a pinion 86 which is provided on the shaft 87 of a suitable source of power such as an electric motor 88. It will be noted from the foregoing that the shaft 81 of the motor drives one train of mechanism composed of gears 86, 82, 22, pinion 23, idler 43, gear 45 and worm screw 47 to provide for the rotation of the rollers 66, 75 and 80 all in a direction to feed the tube 4 endwise at a speed depending upon the ratio of this train of gears. Since the gear 82 is fixed upon the shaft 83, the gear 85 will rotate with the gear 82 at the other side of flange 13, and by meshing with the gear 21 will rotate the bushing 18 at a much faster rate of revolutions per minute than the rollers 66, 75 and 80 will be rotated.

Since the tube 4 is rotated at a rate dependent upon the rotation of the gear 21, this means that the tube will be rotated faster than it will be fed endwise, yet the rotating and endwise moving forces acting on the tube 4 will be derived from the common motor or source of power 88. There is thus a definite predetermined speed ratio between the endwise movement of the tube 4 and its rotary movement, which difference will determine the pitch of the fin which is wound upon the tube 4. By the foregoing mechanism, the tube 4 will be moved endwise progressively through the tubular member 35 and discharged through the outer end of the bushing 36, and at the same time will be rotated about its longitudinal axis. The fin stock is wound upon the periphery of the tube 4 at the discharge end of the flange 36 by mechanism which will next be described.

The fin stock is in the form of a continuous or long stretch of flat, metallic ribbon 89 (Fig. 3). This ribbon is conducted from a spool (not shown) on which a supply of it is coiled, over an idler roller 90 which is free to rotate on a stud 91 mounted on an upstanding bracket 92. From the roller 90, the fin ribbon passes downwardly through a crimping mechanism 93, in which mechanism it passes between opposed crimping rollers 94 where one edge zone of the ribbon is provided with crimps that are shown in Fig. 3. Any suitable crimping mechanism may be employed, and another form of such mechanism is shown for example in Fig. 6 of my prior patent above identified. The ribbon 89 with one crimped edge then passes downwardly to meet the periphery of the tube 4 in a direction tangentially thereto, with the ribbon disposed edgewise of itself against the tube periphery. In other words, the plane of the metallic ribbon is crosswise of the axis of the tube at the zone of contact of tube and ribbon.

One face of the ribbon abuts against the exposed end face of bushing 36, and it is pressed against that bushing by a rotatably mounted disk 95 (Figs. 3 and 4) which at its periphery overlies the end face of the flange on the bushing 36 and closely approaches or touches tube 4. The disk 95 by pressing the ribbon against the end face of the bushing 36 holds the ribbon in edgewise relation to the tube 4 as it is wound thereon. The leading end of the ribbon is fastened to the tube 4 so that it will rotate therewith, then as the tube is rotated and moved endwise, this ribbon will be wound spirally on the tube 4 while held edge-

wise thereto, and this will form a helical fin on the tube 4 as shown on the portion of the tube 4 at the left hand end of Fig. 3.

The disk 95, see Fig. 4, is provided with an integral shaft or stud 96 which is rotatably mounted in suitable ball bearings 97 carried within a tubular sleeve 98. The sleeve 98 is mounted for endwise sliding movement in the bore of a housing 99. A compression spring 100 is compressed between an abutment 101 threaded through one end of the housing 99 and an abutment 102 which is threaded into a threaded bore of the sleeve 98. This spring 100 continuously urges the sleeve 98 endwise in a direction to press a face of the disk 95 at its periphery against the exposed end face of bushing 36, and since the ribbon is between the periphery of the disk 95 and the end face of the bushing 36, the ribbon will be held yieldingly against movement out of an edgewise relation to the tube 4 as it is wound on the tube. The sleeve 98 is provided with a slot 103, which is elongated in the direction of movement of the sleeve 98 under the action of spring 100 and a screw 104 carried by the housing 99 has an end extending into the slot 103 so as to limit the movement of the sleeve 98 under the action of the spring 100 and prevent its hot action. By adjusting the abutment 101 through turning it, the compression on the spring 100 may be varied so that the desired pressure of the disk 95 against the ribbon and the bushing 36 may be adjusted as desired.

The housing 99, Fig. 3, is provided with an arm 105 which is hinged by a bolt or stud 106 on an upright bearing 107 provided on the base of the machine, so that the housing 99 may be swung laterally of its longitudinal axis and carry the disk 95 edgewise of itself toward and from the tube 4. The periphery of the disk 95 is beveled as at 95A, so that when the housing 99 is swung toward the tube 4, this beveled edge 95A will engage against the flange of the bushing 36 and cam the disk in a direction endwise of the tube 4 sufficiently to allow the peripheral edge of the disk 95 to engage the tube 4.

The pivot 106 may be a bolt which when tightened clamps housing 99 in a position where the periphery of disk 95 bears against or is in close proximity to the tube while the machine is in operation. The tube 4 with the fin wound thereon then passes progressively and immediately through the flux-applying device or box 5 where it is treated with a soldering flux and then through the soldering box 6 where solder is applied to secure the fin securely to the tube. The tube with the fin attached and soldered thereon then emerges and passes along the trough 8. Lengths of the tube may be coupled together so that it will be fed progressively through the machine for a considerable period, and the fin will be wound continuously on the connected lengths and soldered thereto. The tube with the fins secured thereon can then be cut into the desired lengths or bent into the desired shapes, depending upon the uses to which the finned tubing is to be put.

In order to limit the angular movement of each of the bell cranks 68 and 69, the housing 25 is provided with a pair of studs 108 and 109. The stud 108 extends through an elongated slot 110 in that arm of bell crank 68 which carries the bearing 77 and mounts the roller 80, and this stud 108 by its engagement with the ends of the slots 110 will limit the possible movement of the bell crank 68 in both directions. When no tube 4 is in position between the rollers 66, 75, and

80, the spring 71 would normally shift the rollers 75 and 80 into contact with the roller 66 and make it difficult to insert a new stretch of tube 4 into the machine. The stud 108, however, limits such movement of the roller 80 to such an extent that no particular difficulty is encountered in inserting a new stretch of tubing 4 which by engagement with roller 80 cams it aside. The stud 109 similarly is received in an elongated slot 111 in the arm of bell crank 69 which mounts the roller 75, and similarly limits the movement of the roller 75 in a direction toward and from the roller 66 for the same reason.

It is believed that the operation of the device for winding the fin stock spirally on the tube will be clear from the foregoing description, and for that reason, it will not be summarized. It will be noted, however, that there is a definite speed ratio between the endwise and rotary movement of the tube 4 which rotation and endwise feeding is caused by different trains of mechanism from a common source of power, so that this ratio when once determined to fix the pitch of the spiral fin, that is the distance between adjacent fins, will remain constant, regardless of the speed of operation of the device. The faster the machine operates, the greater will be the grip on the tube by the rollers which rotate the tube and of the rollers which feed it endwise. The contact between the rollers which feed the tube endwise may be at some distance from the zone of the tube where the fin is applied, because the endwise feeding movement merely causes a compressive action on the tube which does not distort the tube.

If the same rollers rotate the tube also, then there would be considerable twist of the tube between the point of application of the rotating force and the application of the fin thereto, which twist will vary with different speeds and create a non-uniform product. With the rollers which give the tube its rotary motion, separate from the rollers which feed the tube endwise, and engaging the tube as closely as possible to the point of application of the ribbon to the tube, the twist between such rollers and the portion of the tube where the fin is wound thereon will be negligible, and will not produce any material irregularity in the winding of the fin ribbon on the tube. By having the rollers which rotate the tube separate from the rollers which feed it endwise, one may, by changing the speed ratio between the motor and the gears 21 and 22, vary the pitch of the fin as wound upon the tube.

It will be noted from Figs. 3 and 9 that the rollers 66, 75, and 80 are arranged about the axis of the tube 4 at intervals of 120 degrees. This effectively centers the tube, keeps the tube axial, and gives a three point support to the tube. It is also desirable to grip the tube through a considerable peripheral surface zone thereof and if the contact area between each roller and the tube is too extensive, it is difficult to so shape the surfaces of the roller and tube as to provide uniform contact over all the entire abutting areas between the roller and the tube. By using three rollers spaced evenly around the tube, the pressure on the tube will be more uniform and a more effective contact between the concave surface of the roller and the tube can be obtained. I have found that this provides a particularly dependable and efficient feeding means for the tube, and the pressure of the rollers on the tube will be increased by centrifugal action with an increase in speed. For similar reasons three rollers 40

would be advantageous for rotating the tube, but space usually prevents the use of more than two rollers 40. For best results the rollers 40 should be spaced from the exit end of the bushing 36 in distance less than approximately six times the diameter of the tube.

It will be understood that various changes in the details, materials and arrangements of parts, which have been herein described and illustrated in order to explain the nature of the invention, may be made by those skilled in the art within the principle and scope of the invention as expressed in the appended claims.

I claim as my invention:

1. A machine for winding fin stock in ribbon form spirally on the periphery of a tube which comprises a tubular member having a bore therethrough of a size to slidably receive a tube to which a fin is to be applied, means rotatably mounting said member for rotation about the axis of said bore, a plurality of levers mounted on said member for oscillation about axes crosswise of and offset from the axis of said bore, each of said levers having at one end a roller engageable with the tube in said bore close to the exit end of said bore and its other end progressing along said tube and away from its roller in a direction opposite from the direction of travel of said tube and overweighted so as to serve as a centrifugal weight which, when said member is rotated, will move outwardly and force its roller against said tube in said bore with a force increasing with the rate of operation, each of said rollers having a peripheral surface formed to grip said tube sufficiently to cause it to rotate with said member, spring means yieldingly urging said levers in directions to cause said rollers to engage said tube, means for causing endwise movement of said tube through said bore, and means for delivering said fin stock in ribbon form progressively to the portion of the tube leaving said member, with the ribbon abutting edgewise of itself against the periphery of the tube.

2. A machine for winding fin stock in ribbon form spirally on the periphery of a tube which comprises a member, means mounting said member for rotation, said member having a bore concentric with its axis of rotation, means for feeding said tube endwise of itself through said bore, a plurality of levers pivotally mounted on said member for bodily rotation therewith and independently rocking thereon and arranged about said axis equally, each lever mounting a roller on its end nearest the exit end of said bore and contacting said tube in close proximity to said exit end of said bore in a direction radially of the bore, the other arms of said levers extending generally parallel to said axis, from their pivotal mountings in a direction opposite to the movement of the tube through said bore, and overweighted, whereby when said levers rotate with said member, said overweighted arms will be moved outwardly by centrifugal forces and to press said rollers against said tube, spring means yieldingly urging said levers in directions to cause said rollers to grip said tube and cause said tube to rotate with said member as it moves through said bore, and means for delivering said fin stock in ribbon form progressively to the portion of the tube leaving said bore with the ribbon edgewise of and tangentially to said tube so as to be wound spirally on said tube as the tube rotates and moves endwise.

3. A machine for winding fin stock in ribbon form spirally on the periphery of a tube, which

11

comprises a member having a bore of a size to receive and pass said tube, a plurality of rollers engaging said tube at a distance from the exit end of said bore less than six times the diameter of said tube and arranged equally about the longitudinal axis of said bore, and rolling to pass the tube therebetween, levers pivoted intermediate of their ends on said member for rocking movement about pivotal axes lying in planes crosswise of the longitudinal axis of said tube, said levers mounting said rollers on the ends of their arms nearest the exit end of said bore and having the other arms extending generally parallel to the longitudinal axis of the tube and in a direction from their pivots generally opposite to the direction of travel of said tube through said bore, said levers on their said other arms having weights which overbalance the roller carrying ends, spring means urging said levers in directions to press said rollers against said tube, and means for winding the fin stock in ribbon form spirally on said tube at the exit end of said bore.

4. A machine for winding fin stock in ribbon form spirally on the periphery of a tube, which comprises a member having a bore therethrough of a size to slidably receive said tube, three rollers having their peripheries concave in transverse cross section, abutting the periphery of said tube and disposed with their shortest peripheral radii in planes normal to the curved surface of the tube, so that the rollers will have relative rolling motion along the length of the tube, said rollers being arranged 120 degrees apart around the periphery of the tube, levers mounting at least two of said rollers which when rocked will carry the rollers mounted thereon toward and from said tube moving in said bore, spring means for urging said levers in directions to press the rollers carried thereby against said tube and press said tube against the other of said rollers, means mounting said levers for bodily rotation about the longitudinal axis of said tube, and said levers having weighted ends positioned to move by centrifugal forces due to said bodily rotation in directions to press the lever carried rollers against said tube with a force proportional to the speed of rotation, means for rotating all of said rollers at the same speed about their own axes and in the same relative directions to feed said tube endwise, said rollers having peripheral surfaces formed to drivingly grip the tube periphery and feed the tube endwise, and means for winding said fin stock in ribbon form spirally on said endwise moving tube beyond said rollers.

5. A machine for winding fin stock in ribbon form spirally on the periphery of a tube which comprises a member having a housing and aligned extensions at opposite ends thereof, bearings rotatably supporting said extensions on opposite sides of said housing, said extensions having aligned bores therethrough of a size to receive and pass endwise said tube, the tube exit extension having, in close proximity to its exit end radially disposed passages between the exterior thereof and said bore, rollers disposed in said passages, supported by said tube exit extension for bodily rotation therewith and also movement towards and from said tube, and engaging said tube passing through that zone of the bore and disposed for relative rolling movement along the tube as the tube passes them, the peripheries of said rollers being formed to grip a tube passing between them and rotate said tube about its longitudinal axis when the rollers are bodily ro-

12

tated with said tube exit extension about said axis while passing said tube endwise therebetween, means yieldingly urging said rollers into contact with said tube, means disposed in said housing between said bearings for gripping said tube and feeding it endwise of itself through said extensions and housing, a common source of power, and means driven by said source of power for rotating said housing and its extensions about the longitudinal axis of said tube to cause said rollers to rotate said tube about its longitudinal axis at one speed and to operate said feeding means to move the tube endwise at a different speed, whereby a definite ratio of rotative and endwise movements of said tube will occur for all rates of operation of said source of power, and means for winding said fin stock in ribbon form upon the tube at the exit end of said one extension.

20 6. In a machine for winding fin stock in ribbon form spirally on the periphery of a tube, power operated means for simultaneously moving the tube lengthwise of its own axis and also rotating the tube about its own axis, thereby to impart to the tube a screw-like motion, said power operated means including a sleeve through which the tube passes, said sleeve having a face at its discharge end, a guide disk mounted adjacent the end face of the sleeve and adapted to closely abut the same, a shaft for rotatably mounting the disk, a housing for supporting the shaft disposed adjacent the end of the sleeve and being parallel to but offset from the axis of the sleeve, means for directing the fin stock between the guide disk and the end face of the sleeve there to engage a tube passing through the sleeve, and resilient means in the housing constantly urging the guide disk against the end face and interposed fin stock.

40 7. In a machine for winding fin stock in ribbon form spirally on the periphery of a tube, power operated means for simultaneously advancing and rotating the tube thereby to impart to it a screw-like motion, said means having a discharge end, a guide disk mounted on a shaft, said shaft having an axis parallel to but offset from the line of movement of the tube through said power operated means, said disk being mounted normal to the axis of said shaft, a housing for rotatably receiving the shaft, a linearly movable sleeve within the housing provided with bearings in which said shaft is mounted, an end plate for the housing, and a spring disposed between the end plate and said linearly movable sleeve to urge said sleeve, shaft, and disk against the discharge end of said power operated means, and instrumentalities for directing fin stock between said disk and discharge end.

60 8. In a machine for winding fin stock in ribbon form spirally on the periphery of a tube, a rotatable housing, sleeves secured to and concentric with the housing and formed with aligned bores adapted to receive a length of tubing to be wound, power driven rollers in the housing adapted to grip a tube passing therethrough and to advance said tube through the housing in a lengthwise direction, a bearing adjacent the sleeve on the discharge side of said housing to rotatably support said sleeve, said last named sleeve overhanging said bearing in the direction of movement of the tube, a second housing mounted on said last named sleeve for rotation therewith, a second set of rollers rotatably mounted in said second housing, supporting means in said second housing disposed between

13

the axes of said second rollers and said bearing for urging said second rollers into gripping engagement with a tube passing through said sleeve, whereby upon rotation of said housings said gripping rollers will rotate the tube as it is advanced through the housings by said power driven rollers, and means adjacent said gripping rollers and the discharge end of said second housing for directing fin stock around the periphery of the tube.

9. In a machine for winding fin stock in ribbon form spirally on the periphery of a tube, a rotatably mounted housing provided with concentrically disposed sleeves on either side for supporting the housing and receiving a tube to be wound, means in the housing for engaging a tube and moving it lengthwise through the sleeves and housings; a second housing mounted on the sleeve at the discharge end of the first housing for rotation therewith, bell crank levers pivotally mounted in said second housing for movement about axes transverse to the line of motion of a tube through said sleeves, one arm of each of said levers extending toward both the discharge end of said sleeve and the longitudinal axis of the sleeves and tube passing therethrough, gripping rollers mounted at the ends of each of said arms, means urging said arms and the rollers carried thereby into gripping engagement with a tube passing through the housings, whereby upon rotation of the housings the tube will be rotated about its own axis as it moves endwise, and fin stock applying means located adjacent said gripping rollers to supply said fin to the tube before said tube is torsionally distorted.

10. In a machine for winding fin stock in ribbon form spirally on the periphery of a tube, a rotatable housing provided with concentric sleeves through which a tube may pass, means in said housing for advancing a tube lengthwise through said sleeves from an entrance end to a discharge end, a second housing mounted on and rotatable with one of said sleeves adjacent the discharge end thereof, pivot pins mounted in said second housing with their axes transverse of the line of movement of the tube, bell crank levers mounted on said pins, one arm of each of said levers extending generally parallel to said line of movement and the other arm of each of said levers extending toward the discharge end of said second housing and the longitudinal axis of said tube, rollers mounted on said last named arms for engagement with the tube, and resilient means interposed between the sleeve and the first named arms to urge said rollers into gripping engagement with the tube.

11. In a machine for winding fin stock in ribbon form spirally on the periphery of a tube, a rotatable drum housing having concentric

14

sleeves through which the housing is mounted, said sleeves having aligned bores through which a tube may pass endwise, means in the drum housing for advancing the tube lengthwise through the sleeves from an entrance end to a discharge end as the drum is rotated, an extension sleeve piece connected to the discharge end of one of the drum housing sleeves, said extension piece being formed with elongated and lengthwise disposed slots terminating adjacent the discharge end, ribbon guiding rolls disposed at said end to direct the ribbon stock onto the tube, and pivotally mounted rollers mounted on said extension sleeve piece and projecting into said slots to grip a tube for rotation.

12. In a machine for winding fin stock in ribbon form spirally on the periphery of a tube, a drum housing provided with concentric sleeves for rotatably mounting the drum, bearings for supporting the sleeves, a plurality of rollers mounted within the drum about the longitudinal axis of the drum and sleeves, each of said rollers having a shaft angularly disposed to adjacent rollers and each of said rollers having a peripheral portion positioned adjacent said longitudinal axis to engage a tube passing therethrough, bevel gearing secured to said shafts and interconnecting the rollers for concurrent rotation, a power gear connected to one of said shafts, a driven gear train, said driven gear train including a terminal gear meshing with said power gear to rotate the same and thereby the rollers, and a second gear train connected to said first named driven gear train and to one of said sleeves to effect the simultaneous rotation of said sleeves and said drum.

13. In a machine for winding fin stock in ribbon form spirally on the periphery of a tube, a machine frame provided with spaced pedestal bearings, a rotatably mounted drum housing provided with concentric sleeves mounted on said bearings, a fixed housing adjacent said drum housing and encircling one of said sleeves, a power input gear train mounted on said frame and in said fixed housing, a gear on one of the sleeves meshing with the terminal gear of said train, a second power input train connected to said first named train and including a terminal gear rotatably mounted on the said gear-receiving sleeve, tube advancing rollers mounted in said drum housing and adapted to engage a tube to advance the same through said sleeves and drum, and gearing connecting said rollers to said rotatable terminal gear, said gear trains including idlers whereby the relative rates of rotation and advance may be varied by changes of gears and said rates are fixed with respect to each other when said trains are complete.

JOSEPH D. LEAR.
